(57) **CLAIM**

The ornamental design for a display for fragrance and cosmetic sampler, as shown and described.

DESCRIPTION

FIG. 1 is a top view of the display for fragrance and cosmetic sampler showing our new design;
 FIG. 2 is a bottom view thereof;
 FIG. 3 is a back view thereof;
 FIG. 4 is a front view thereof;
 FIG. 5 is a right side view thereof;
 FIG. 6 is a left side view thereof;
 FIG. 7 is a perspective view of the display for fragrance and cosmetic sampler shown with environment; and,
 FIG. 8 is another perspective view of the display for fragrance and cosmetic sampler shown with the environment in an alternate state.
 The broken lines depict environment that form no part of the claimed design.

1 Claim, 8 Drawing Sheets
